UNITED STATES PATENT OFFICE.

CORNELIUS D. EHRET, OF ROSEMONT, PENNSYLVANIA.

WIRELESS SELECTIVE SIGNALING SYSTEM.

SPECIFICATION forming part of Letters Patent No. 717,978, dated January 6, 1903.

Application filed July 3, 1902. Serial No. 114,169. (No model.)

To all whom it may concern:

Be it known that I, CORNELIUS D. EHRET, a citizen of the United States, residing at Rosemont, in the county of Montgomery and State of Pennsylvania, have invented a new and useful Wireless Selective Signaling System, of which the following is a specification.

My invention relates to signaling systems, more especially those in which electroradiant energy is employed.

More particularly it refers to selective signaling systems in which energy of a definite frequency is generated and modified at the transmitting-station and which is transmitted through the natural media and is received in circuits at the receiving-stations, which are so proportioned as to their electrical constants as to respond to such energy of a definite frequency to the exclusion of other energies.

It further refers to a method of generating in a predetermined order of succession energies of different frequencies and putting the receiving device into communication with such energy in a predetermined manner, so as to select the transmitted energies to the exclusion of other energies and in the same order as transmitted.

It comprises, further, a method of cyclically generating different frequencies and cyclically receiving different frequencies to reproduce a signal, and, furthermore, to cyclically produce a plurality of frequencies simultaneously and to receive in the same order a plurality of frequencies simultaneously, which operate conjointly to reproduce a signal or which operate separately to produce separate signals.

It has heretofore been suggested that electric energy of a definite frequency be generated and the receiving apparatus be so attuned as to its electrical constants so as to receive that energy only and to the exclusion of all others, whereby secrecy of communication could be obtained. It is possible, however, with such system for an undesired party to read the messages transmitted, for it is only necessary for him to gradually vary the constants of his receiving system until they are such as to select the energy being transmitted. This would require in many instances but a

few moments' trial and would then render the so-called "selective" system non-secret. By the method and apparatus herein described it is seen that the frequency of the energy representing a signal is changing cyclically and at regular intervals and that the receiving device is changed as to its electrical constants simultaneously and in the same order. This cycle of operation occupies a period of time, however, which is quite short, and it is necessary that for one code character energy of all frequencies must be transmitted. In other words, for each code character energies of several frequencies are transmitted and received, and in consequence any one trying to adjust a simple receiving device to interrupt such message would fail, because he could adjust to not more than one of such frequencies, and in consequence, due to the relatively slow operation of the apparatus, he would receive a series of dots which would mean nothing whatsoever. By the method and apparatus herein described, therefore, it is apparent that the possibility of secret communication is greatly enhanced and the probability of undesired parties reading the message is greatly reduced.

Reference is to be had to the accompanying drawings, in which—

Figure 1 is a diagrammatic view of a transmitting-station for transmitting energies of four different frequencies in a certain order of succession and in which the inductance elements are entirely isolated from the aerial conductor except for one-quarter of the time. Fig. 2 is a diagrammatic view of a receiver adapted to cooperate with the transmitter shown in Fig. 1. Fig. 3 is a modified form of circuit arrangement for a transmitter. Fig. 4 is a diagrammatic view of a receiver adapted to cooperate with the transmitter shown in Fig. 3. Fig. 5 is a diagrammatic view of a modified form of transmitter. Fig. 6 is a diagrammatic view of a modified form of a transmitter in which the frequency of the radiated energy is changed from instant to instant by means of changing the capacities in an oscillating circuit. Fig. 7 is a modified form of transmitter in which two energies of different frequencies are simultaneously radiated and from moment to moment the frequency of

each of the energies is changed. Fig. 8 is a diagrammatic view of a modified form of transmitter in which a plurality of energies are simultaneously radiated and of different frequencies and such energies changed as to their frequency from moment to moment. Fig. 9 is the receiving device to coöperate with the circuit shown in Fig. 8, in which two energies of different frequency are simultaneously received to conjointly produce a signal. Fig. 10 is a diagrammatic view of a transmitter by which two messages are simultaneously sent from the same aerial conductor and the energy representing each message is cyclically changed as to its frequency. Fig. 11 is a diagrammatic view of a receiver adapted to coöperate with the transmitter shown in Fig. 10, by which two messages are simultaneously received. Fig. 12 is a modified form of receiver by which two messages are simultaneously received.

In Fig. 1, A is the usual aerial conductor of a wireless signaling system. At its lower end it is in electrical communication with the trailer 1, which is driven by means not shown at a comparatively slow rate over four segments of the sunflower B. 2, 3, 4, and 5 are the inductances of different magnitudes, which connect at their upper ends to the segments of the sunflower B' and at their lower ends with corresponding segments of the sunflower B', over which is driven at the same speed as trailer 1 the trailer 6, which is in electrical communication with one terminal 35 of the spark-gap S, whose remaining terminal connects to the earth-plate E. In the position shown there is in series between the spark-gap S and the aerial conductor inductance 3, which when taken in conjunction with 40 said aerial conductor serves to determine the frequency of the energy radiated from the aerial conductor A during the time that the trailers 1 and 6 are passing over the segments to which said inductance 3 is connected. Supposing the trailers 1 and 6 to be rotating in a clockwise direction, the inductance 3 is after a time entirely out of circuit, and the inductance 2 is brought into circuit, thereby causing energy of different frequency to 45 be radiated from the aerial conductor A. In the same manner the remaining inductances 5 and 4 are brought successively into circuit, and there results, therefore, a radiation of energy of four different frequencies 50 for each revolution of the trailers 1 and 6. In shunt to the spark-gap S is the usual secondary of a transformer or induction-coil, in whose primary is the usual Morse key to control the energy according to a telegraphic 55 code. The rate of rotation of the trailers 1 and 6 and also those in the figures hereinafter to be described is such that for the longest code character an entire revolution must be made. It results from this that an undesignated party adjusting his receiving device so as to select any one of the frequencies radiated from the aerial conductor A, which re-

ceives an impulse only once in a revolution and so, therefore, receives nothing but a series of dots.

In Fig. 2 is shown the receiving device adapted to coöperate with the transmitter shown in Fig. 1. Like reference characters refer to like parts. To the trailer 1 is connected the conductor 7, which leads through the small condenser k to the wave-responsive device 8, thence through the small condenser k to the trailer 6. Trailer 6 is also connected to earth-plate E. It is apparent, therefore, that the wave-responsive device is in shunt 75 at every instant to one or other of the inductances 2, 3, 4, and 5 and is subjected to a very great potential difference. In shunt to the wave-responsive device 8 is the usual relay 9, whose tongue 10 controls the local circuit, as is well understood in this art. The source of energy 11 is connected between the coils of the relay 9, which coils operate then as the usual choke-coils. The object of the condensers k k is to prevent the flow of energy from source 11 through any of the inductances 2, 3, 4, or 5, which were it to occur would keep the relay 9 constantly energized and no signals could be received. The trailers 1 and 6 revolve synchronously at the 85 transmitting and receiving station, and in consequence when inductance 2 is in circuit at the transmitter inductance 2 is in circuit at the receiver, and the receiver is therefore at every instant selective of the energy transmitted.

In practice the sunflowers B B' should not be flat; but the several segments would be arranged similarly to the teeth of the ratchet, in which case the trailers 1 and 6 would be 90 brushes which would snap quickly from one segment to the other, and the synchronous rotation of the trailers or sunflowers at each of the stations may be procured by rotating them on an arbor of a chronometer or by a 95 chronometer which at certain intervals closes the circuit to control the speed of rotation, and to adjust to exact synchronism the brushes or trailers 1 or 6 can be slightly changed in their angular position.

In Fig. 3 but a single sunflower is employed, and greater portions of the inductance-winding are cut into the circuit of the aerial conductor A. Portion 12 of the inductance is always in circuit, and when trailer 13 of the 100 sunflower B is in the position shown the inductance 12 only is in circuit. As it moves in a counter-clockwise direction onto the next contact the portions 12 and 14 are both in circuit with the aerial conductor. On the 105 next contact portions 12, 14, and 15 are in circuit and on the next contact portions 12, 14, 15, and 16 are in circuit. S is the spark-gap, as described in connection with Fig. 1, whose one terminal connects to the trailer 13 110 and whose other terminal connects to the earth-plate E. It is seen, therefore, that there are cyclically radiated energies of different frequencies, according as the different

amounts of inductances are in circuit with the aerial conductor A.

In Fig. 4 like characters refer to like parts in connection with Fig. 3 and represent the arrangement of circuits in a receiver to operate in conjunction with the transmitter shown in Fig. 3. Trailer 13 revolves synchronously at two stations, so that at each instant the receiver is capable of selecting energy radiated at the transmitter. Trailer 13 of the receiver is connected to earth-plate E through the wave-responsive device 17, in shunt to which is the usual relay 18, whose tongue 19 controls the local circuit, as is well known in this art. 20 is the source of energy for such relay-circuit, and is connected between the coils of the relay 18.

In Fig. 5, 21 represents an alternator or other source of alternating or pulsatory currents, which is in circuit with the primary 22 and the key 23. The secondary 24 has connected between its terminals the spark-gap S, one of whose terminals connects to the earth-plate E and whose other terminal connects to the trailer 25. Trailer 25 rotates and passes successively over the segments of the sunflower B, to whose segments are connected various inductances, but in such a manner that the trailer 25 progressively short-circuits sections of inductance. The section of inductance 26 is always in circuit. In the position of the trailer as shown it is short-circuiting the lower section 30 of inductance. Revolving in a clockwise direction in passing to the next section it short-circuits both 29 and 30 of the inductance. On the next section it short-circuits 28, 29, and 30. On the last segment it short-circuits 27, 28, 29, and 30, leaving only 26 in circuit. This is merely a modified manner of obtaining energies of different frequencies.

In Fig. 6, 31 is an alternator or other source of alternating or pulsatory currents, which is in circuit with the telegraphic key 32 and the primary 33. The secondary 34 is shunted to the spark-gap S, and in shunt to said spark-gap S is the inductance 35 or the primary of the transformer in series with the sunflower B and trailer 36, by means of which the condensers of different capacities—namely, 37, 38, 39, and 40—are successively brought into action. With the trailer in the position shown the condenser 38 only is in action and determines the frequency of oscillation of the circuit S, 35 36 38. When rotating in a clockwise direction, the trailer will next bring condenser 39 into circuit, and thereby change the frequency of oscillation, and the same is true for the remainder of the segments. The secondary 41 is in series between the aerial conductor A and the ground-plate E. By depressing key 32, therefore, there results radiation from the aerial conductor A of four different frequencies successively.

In Fig. 7 is shown an arrangement for simultaneously transmitting energies of different frequencies to be radiated from the aerial

conductor A, which is common to both the transmitters. In series with aerial conductor A is the inductance 42, of which the upper 70 section is always in circuit. The sunflowers B B' each control different portions of the inductance by virtue of the trailers 43 and 44 rotating over the segments of each sunflower. In so doing they cut in and out greater or less 75 portions of inductance in addition to the inductance 42, and the trailer 43 always controls different amounts of inductance from those controlled by trailer 44, so that at the same instant of time energies of different frequencies are being radiated. It appears, therefore, that energies of four different frequencies are controlled by trailer 43, and four energies of still different frequencies are controlled by trailer 44, and that two of them are 85 simultaneously radiated.

In Fig. 8 is shown an arrangement of circuits for transmitting from the aerial conductor A two energies of different frequencies simultaneously. 45 is an alternator or other source 90 of alternating or pulsatory currents, which is in circuit with the key 46 and the two primary coils 47 and 48. The secondary 49 is bridged by the spark-gap S, whose one terminal connects to earth-plate E and whose other 95 terminal connects to the trailer 50. This trailer moves over the segments of the sunflower B, and thereby cuts out more or less of the inductance 51, whose upper section is always in circuit. The secondary 52 is bridged 100 by the spark-gap S', whose one terminal connects to earth-plate E' and whose other terminal connects to trailer 53, moving over the segments of the sunflower B' to cut in and out more or less inductance, of which one section 54 is always in circuit. From this arrangement there results a simultaneous transmission of two energies of different frequencies, and the frequency of each energy is cyclically varied. Care must be observed in 110 the connection of the secondaries of the transformers shown in this figure and Figs. 7 and 10 in order that there may be no short-circuiting of the secondaries through the earth-plates E E' and the inductances. For this 115 purpose condensers k k' of small capacity are connected as shown. The low-frequency currents from the transformers are restrained by the condensers, whereas these condensers are no hindrance to the high-frequency oscillations. 120

In Fig. 9 is shown the receiving apparatus adapted to operate in conjunction with the transmitter shown in Fig. 8. Herein like characters refer to similar parts as appearing in Fig. 8. In shunt to the inductance 51 is connected, through the condensers k , the wave-responsive device 55, in shunt to which is the relay 56, whose tongue is represented at 57. In shunt to the inductance 54, through the condensers k' , is the wave-responsive device 58, in shunt to which is the relay 59, whose tongue is represented at 60. The relay 56 is energized by battery 61, and relay 59 is en-

ergized by battery 62. The trailers 56 and 53 of the receiver are arranged symmetrically with those of the transmitter, and in consequence at each instant there are received two energies of different frequencies, which then control the wave-responsive devices 55 58, resulting in the simultaneous control of the relays 56 and 59. This results in the tongues 57 and 60 coöperating with their contacts and close the circuit embracing the source of energy 63 and the recording-relay 64, whose tongue 65 controls the final recording-circuit. From moment to moment, however, the energies received change their frequencies; but at all times two energies are being received which differ in frequency. This arrangement insures great privacy because of the great difficulty encountered by any one attempting to adjust his apparatus to receive a message.

In Fig. 10, 66 and 67 are alternators or other source of alternating or pulsatory currents, which are controlled by keys 68 and 69, respectively, of the primaries 70 71, respectively. 72 is the secondary of the primary 71 and connects to the spark-gap S, whose one terminal connects to earth-plate E and whose other terminal connects to trailer 73, which revolves over the segments of the sunflower B, thereby short-circuiting more or less of the inductance 74, of which there is always a section in circuit. 75 is a secondary of the transformer 70 and is bridged to spark-gap S', one terminal of which connects to the earth-plate E' and whose other terminal connects to trailer 76, moving over the segments of the sunflower B', thereby short-circuiting more or less of the inductance 77, of which the upper portion is always in circuit. By this means two simultaneous messages may be simultaneously transmitted through the aerial conductor A, each one represented by energy of a different frequency and each energy changing in its frequency from moment to moment, according to the position of the trailers 73 and 76.

In Fig. 11 is shown the receiver adapted to operate in connection with the transmitter shown in Fig. 10, in which like characters refer to similar parts in Fig. 10. In series between the aerial conductor and inductances 74 is a wave-responsive device 78, in shunt to which is the relay 79, energized by the source of energy 80, and whose tongue 81 controls the recording-circuit. In series with inductance 77 and the aerial conductor A is the wave-responsive device 82, in shunt to which is the relay 83, energized by the source of energy 84, and whose tongue 85 controls the recording-circuit. By this means two independent messages are simultaneously received on the aerial conductor and selected to their proper recording-circuits, and at the same time the constants of each of these circuits upon which its selectivity depends change from moment to moment.

In Fig. 12 is shown a modified arrangement of receiver for receiving simultaneously from the small aerial conductor A two independ-

ent messages. In this case inductance 86 is common to both sunflowers B B', but different amounts are tapped off to the segments of each sunflower over which move the trailers 87 and 88. From the trailer 88 is a connection to the primary 89, whose remaining terminal connects to earth-plate E. 90 is the secondary of such transformer, which connects through the small condensers k with the wave-responsive device 91, in shunt to which is the relay 92, energized by battery 93, and whose tongue 94 controls a recording-circuit. From the trailer 87 there is a connection to the primary 95, whose remaining terminal connects to earth-plate E'. 96 is the secondary of such transformer, whose terminals connect to the small condensers k' to the terminals of the wave-responsive device 97, in shunt to which there is relay 98, energized by battery 99, and whose tongue 100 controls the local recording-circuit. The functions of the small condensers k k' are to prevent a flow of current from 93 and 99 through the secondaries 90 and 96, respectively. By the arrangement herein shown there may be received simultaneously two energies of different frequencies, which energies change their frequency from moment to moment. The trailers 87 and 88 rotate synchronously with the trailers at the transmitting devices, such as shown in Figs. 8 and 10, and the inductances are so chosen as to make the receiving-circuit selective of the proper energy at the proper moment.

From the arrangement of apparatus and of the circuits herein described it is apparent that greater secrecy may be obtained than in the usual simple selective system, for the reason that an undesired party would be unable to adjust his device so as to be selective of more than one frequency.

In the system herein described tuning is resorted to; but it is characteristic that the rate is changed from time to time in a certain cycle of operations, and, furthermore, in some of the arrangements shown a plurality of energies of different characteristics operating simultaneously are necessary to produce a signal. It follows, therefore, that the probability of an undesired party interrupting a message is extremely remote, due to the great number of dependent circumstances, the probability becoming very small due to such fact.

What I claim is—

1. The method of transmitting intelligence, which consists in emitting in a predetermined order of succession, energies differing in properties, and subjecting a wave-responsive device at the receiver to said energies in an order of succession corresponding with the order of succession of their emission.

2. The method of transmitting intelligence, which consists in emitting energies, representing a message, in a predetermined order of succession, and simultaneously subjecting a wave-responsive device at the receiver to said energies in the same order of succession.

3. The method of transmitting intelligence, which consists in generating and emitting electroradiant energy representing a signal or message, cyclically varying a characteristic of said energy, and subjecting a wave-responsive device at the receiver to the cyclically-varying effects of said energy. 70
4. The method of transmitting intelligence, which consists in generating electroradiant energy, cyclically varying a characteristic of said energy, controlling said energy to represent elements of a signal or message, and simultaneously subjecting a wave-responsive device at the receiver to the cyclically-varying effects of said energy. 75
5. The method of transmitting intelligence, which consists in generating electrical energy, cyclically varying the frequency of said energy, and simultaneously subjecting a wave-responsive device at the receiving-sta- 80
- 20 tion to the cyclically-varying effects of said energy. 85
6. The method of transmitting intelligence, which consists in generating electrical energy, cyclically varying the frequency of said energy, and simultaneously subjecting a wave- 90
- 25 responsive device to the cyclically-varying effects of the varying frequency of the trans- mitted energy. 95
- 30 7. The method of transmitting intelligence, which consists in generating electroradiant energy, varying a characteristic of said energy in a series of steps in a predetermined order of succession, and simultaneously sub- 100
- 35 jecting a wave-responsive device at the receiver to the effects of the received energy in the same order of succession. 105
- 40 8. The method of transmitting intelligence, which consists in generating electrical energy, cyclically varying a characteristic of said energy, and simultaneously subjecting a wave- 110
- 45 responsive device at the receiver to the cyclically-varying effects of said energy in a plurality of circuits selective of the different effects of said energy. 115
- 50 9. The method of transmitting intelligence, which consists in generating electrical energy, controlling said energy to represent a signal or message, cyclically varying a characteristic of said energy, and cyclically bringing a wave- 120
- 55 responsive device at the receiver into the influence of a plurality of circuits, each circuit being selective of the effects of the transmitted energy when having a predetermined characteristic. 125
- 60 10. The method of transmitting intelligence, which consists in generating electrical energy, cyclically varying the characteristic of said energy, and cyclically bringing a wave- 130
- 65 responsive device at the receiver into the influence of a plurality of circuits, each circuit being selective of and producing the maximum effects of the transmitted energy when having a predetermined characteristic. 135
- 65 11. The method of transmitting intelligence, which consists in generating electrical energy, controlling said energy to represent a signal or message, cyclically varying the frequency of said energy, and cyclically bringing a translating device at the receiver into the influence of a plurality of circuits, each circuit being selective of the effects of the transmitted energy when having a predetermined frequency. 140
12. The method of transmitting intelligence, which consists in generating electrical energy, cyclically varying the frequency of said energy, controlling said energy to represent a signal or message, and cyclically bringing the translating device at the receiver into 145
- 70 the influence of a plurality of circuits, each circuit being selective of and manifesting the maximum effects of the transmitted energy when having a predetermined frequency. 150
13. The method of transmitting intelligence, which consists in simultaneously generating a plurality of electrical energies, controlling said energies to represent a signal or message, cyclically varying a characteristic of each of said energies, and cyclically bringing a plurality of wave-responsive devices at the receiver into the influence of a plurality of sets of circuits, each circuit of a set being selective of the effects of a transmitted energy when having a predetermined characteristic. 155
14. The method of transmitting intelligence, which consists in simultaneously generating a plurality of electrical energies, controlling said energies to represent a signal or message, cyclically varying the frequency of each of said energies, and cyclically bringing a plurality of translating devices at the receiver into the influence of a plurality of sets of circuits, each circuit of a set being selective of the effects of a transmitted energy when having a predetermined frequency, and said translating devices operating conjointly to produce a signal or message. 160
15. The method of transmitting intelligence, which consists in emitting energy representing a signal or message, cyclically varying a characteristic of said energy, the duration of a cycle being equal to the duration of the shortest element of the signal, and sub- 165
- 110 jecting a wave-responsive device at the receiver to the effect of the received energy. 170
16. The method of transmitting intelligence, which consists in generating energy, varying a characteristic of said energy through predetermined values during an interval of time equal to the duration of the shortest code character, repeating the variation cyclically, and simultaneously subjecting a wave-responsive device at the receiver to the cyclically-varying effects of said energy. 175
